UNITED STATES PATENT OFFICE.

HARRIE A. BALLARD, OF ASHLAND, MASSACHUSETTS, ASSIGNOR, BY MESNE ASSIGNMENTS, TO THE BOYLSTON MANUFACTURING COMPANY, OF BOSTON, MASSACHUSETTS, A CORPORATION OF NEW JERSEY.

MACHINE FOR TACKING SHOES.

1,015,931.

Specification of Letters Patent.

Patented Jan. 30, 1912.

Application filed January 28, 1904, Serial No. 190,932. Renewed June 1, 1910. Serial No. 564,454.

To all whom it may concern:

Be it known that I, HARRIE A. BALLARD, of Ashland, in the county of Middlesex and State of Massachusetts, have invented certain new and useful Improvements in Machines for Tacking Shoes, of which the following is a specification.

This invention has for its object to provide a pulling-over machine for boots and shoes, with means by which the pulled-over portion of the upper may be fastened to the innersole, and it has further for its object to provide a machine of the character described by means of which the manipulation 15 of the shoe may cause the actuation of the fastener-driving mechanism so that while said mechanism is controlled manually, yet it is set in motion by the manipulation of the shoe rather than by the manipulation 20 of some other portion of the machine, as, for instance, a lever or treadle.

According to the illustrated embodiment of the invention which is hereinafter described in detail, the machine may be provided with a gripper which may be closed 25 manually to grip the edge of the upper. This gripper may for convenience be formed, in part, of the fastener-delivering nozzle, serrated on one face for the purpose, and a 30 jaw pivoted to the nozzle to co-act with the serrated face thereof and adapted to be actuated by a foot-treadle. The movable jaw is so arranged and located that it constitutes an abutment for the shoe, about 35 which the shoe may be swung by the operator to draw the upper bodily about the last, to position it properly with respect thereto, so that its median line will coincide with the median line of the last.

40 The invention may be conveniently embodied in a machine having mechanism for automatically feeding and driving tacks, but it will be understood that any other form of fastener and fastener feeding and 45 driving means may be utilized in lieu thereof.

Reference is to be had to the accompanying drawings, forming a part of this specification, of which—

50 Figure 1 represents in side elevation a tacking-machine embodying the several features of this invention, and a portion of a shoe in process of lasting. Fig. 2 represents an elevation of the opposite side of

the machine. Fig. 3 represents a front elevation with the shoe omitted. Fig. 4 is a section on the line 12—12 of Fig. 2. Fig. 5 is a section on line 13—13 of Fig. 2. Fig. 6 shows the driver-bar in a lowered position. Fig. 7 is a perspective view of the nipple-bar and nipple. Figs. 8 and 9 show the method of pulling the upper over the inner-sole of the shoe before the tack is driven. Fig. 10 represents a section on the line 18—18 of Fig. 1.

On the drawings,—10 represents the head or frame of the machine, which is mounted on a suitable standard, the upper portion of which is shown at 11, in Fig. 3.

The tack-driver is indicated at *o* as attached to the lower end of a driver-bar 1. The said driver receives its motion from a shaft 12, journaled in bearings 13 13 in the head 10. The shaft 12 is rotated by a continuously-driven clutch-pulley of suitable 75 construction, shown at 14 as mounted on said shaft. On the end of the shaft 12, adjacent the driver-bar is affixed a crank-disk 15 provided with a crank-pin 16. A roller 17 on the crank-pin 16 travels in a slot 18 80 in the driver-block 19, to which the driver-bar is attached. By virtue of this construction and arrangement, the rotation of the shaft 12 effects the vertical reciprocation of the driver-bar 1. As hereinafter described, 85 provision is made whereby the range of reciprocation of the driver-bar 1 may be varied.

The nipple-bar 20, to the lower end of which is attached the tack-delivering nipple 21 and the gripping-lever 22, is adapted 90 to slide in guides 23 23 in the head 10. A backwardly-projecting extension 24 of said nipple-bar engages the mechanism which causes the pulley 14 to clutch and drive the 95 shaft 12 and automatically release and stop said shaft at the end of one complete revolution. Said mechanism comprises a plunger 25, which is mounted in a boss on the head 10. The upper end of said plunger is 100 provided with a beveled face 250, which engages a projection 26 on the shaft 12. Said projection extends through the shaft to the clutch contained in the pulley 14. The clutch may be of any suitable construction which need not be specifically described. 105 The plunger 25 is normally held upward by a spring 27, and its lower end is connected

to a tripping-lever 28. Said lever extends forwardly to the nipple-bar 20 and is fulcrumed at 29 to the head 10. A latch 30 pivoted at 300 to the forward end of the lever 28 rests on the extension 24 of the nipple-bar 20, and is held against said extension by a spring 31. A finger 32 on the latch 30 engages an adjustable stop 33, in such manner that when said latch is raised by the extension 24, it raises the forward end of the lever 28 and is caused to oscillate on its pivot 300 until it has ridden off the end of said extension. In consequence of the freeing of the latch 30 from the extension 24, said latch is not affected by any further upward movement of said extension and the lever 28 is free to be returned to its former position by the spring 27. Not until the extension 24 has dropped to its former position does the latch 30 spring into place on said extension.

50 50 indicate the two inclined tack-races which receive the tacks from tack-reservoirs 51 51, one containing long and the other 25 short tacks. Said races converge toward each other near the driver *o*, but their slots 52 52 do not quite meet. At the lower end of the races 50 is the tack-feeder 53 mounted in a boss 54 on the head 10, and adapted to 30 slide back and forth across the path of the tacks. Said feeder or tack-pick and the race-way may be moved one with relation to the other by any convenient means to cause the feeding of the tacks successively to the 35 nipple. This mechanism may conveniently include a bell-crank-lever 70 fulcrumed at 71 to an ear projecting from the head and having its downwardly extending arm connected by pin 72 to the feeder 53. The other 40 arm of the lever may be connected by a link 73 to an adjustable stud 74 depending from the extension 24 of the nipple-bar 20. By reason of this construction, the vertical reciprocation of the nipple-bar causes the actuation of the tack-pick or feeder.

45 As previously stated, a gripping-lever 22 is mounted at the lower end of the nipple-bar 20, and is fulcrumed on a stud 61 passing through an ear on said nipple-bar. A 50 link 62 connects the upper end of the lever 22 to one arm of a bell-crank-lever 63 fulcrumed on a stud 64 on the head 10. The other arm of the lever 63 is connected by a thrust-rod 65 to a treadle (not shown) at the 55 base of the standard 11.

A shoe to be lasted is presented to the tack-delivering nipple 21, so that the edge of the upper *a* projects between said nipple and the lower end of the gripping lever 22, 60 as shown in Fig. 8. The inner faces of said nipple and gripping lever are provided with teeth, as indicated at *x* and *y*. A depression of the treadle already referred to causes the teeth *y* to close on the edge of the upper *a* 65 which is held between the two rows of teeth

x and *y*. The shoe is then given a forward and upward rocking motion, which causes the innersole *b* to bear against the rounded shoulder 220 of the lever 22, (see Fig. 9.) This affords a good purchase on the upper *a* 70 and pulls it well over the edge of the innersole *b*. By continuing the tension on the upper and at the same time rocking it back to the position shown in Fig. 1, the shoe is ready to receive a tack. 75

It will be remembered that the nipple-bar 20 may have a slight upward movement in its guides 23 23. By pressing the shoe upwardly, still retaining the necessary tension on the upper, the nipple-bar 20 and its extension 24 will be raised so that the link 73 and lever 70 will actuate the tack-feeder 53, thereby transferring a tack from one of the races 50 to the bore 60 of the nipple-bar 20, and at the same time the extension 24 will 80 press upwardly the latch 30 which causes the lever 28 to withdraw the plunger 25 from the projection 26 which automatically clutches the pulley 14 to the shaft 12. Thus the driver is caused to descend on the tack 85 already placed in the bore 60 of the nipple-bar 20 and drive said tack into the shoe. The latch 30 is so adjusted by the stop 33 that when the nipple-bar has reached its upper extreme, said latch, by reason of the 90 stoppage of its arm 32 by said stop, rides off the end of the extension 24, and this allows the spring 27 to return the plunger 25 to its former position in the path of rotation of the projection 26. As the projection 95 rotates, it engages the beveled face 250 of the plunger 25 and simultaneously unclutches the pulley 14 and arrests the rotation of the shaft 12 at the completion of one revolution. The shoe and nipple-bar 20 are 100 then lowered, allowing the latch 30 to spring into place on the extension 24, the lever 22 is released, the shoe moved to another position, and the same operation repeated.

The race-ways are preferably connected at 110 their lower ends and they, together with the tack reservoirs, are pivoted upon a vertical axis so that the lower end of the race-ways may be moved laterally to bring the end of either race-way into operative position with 115 respect to the tack-feeder. The finger-lever 78 engages a pin 79 on one of the races so that, as the lever 78 is rocked up or down, it shifts the race-ways upon a vertical axis in one direction or the other. A spring 80 120 serves to hold the lever 78 in either of its two positions.

Provision is made for driving the tacks to a greater or lesser depth in the shoe by a shifting mechanism in the block 19 on the 125 driver-bar 1. Said driver-bar is connected to the block 19 by a sleeve 91 contained in the block and in which the driver-bar is held by collars 92 92 pinned to the driver-bar. A stud 93 which is affixed to the sleeve 91 130

projects through a slot 94 in the block 19 and into a cam-slot 95 of a sliding-plate 96. Said plate is held in the block 19 by gibbs 97 97. By sliding the plate 96 to one end or 5 the other in the block 19, its cam-slot 95 co-acting with the stud 93, raises or lowers the sleeve 91 in relation to the block 19. Hence the range of throw of the driver-bar 1 is raised or lowered. In view of the fact that 10 no jack is employed, a spring 98 on the driver-bar is interposed between the sleeve 91 and lower collar 92 to absorb the shock which the operator would otherwise receive from the blow delivered by the driver-bar, 15 but at the same time is of sufficient strength to drive the tack.

From the foregoing description, it will be apparent that the tack-feeding mechanism and the tack-driving mechanism are independently actuated, and that both are controlled by the tack-nozzle or nipple, or by the pincer or gripper.

For convenience of phraseology I have referred to the fastener driving and feeding mechanism as the "tacking mechanism" or "tack-feeding mechanism", but I desire to have it understood that those terms are used in no limiting sense and that as previously stated herein, mechanism for feeding and 30 driving nails, pegs, or other fastenings may be utilized in lieu thereof, without departing from the spirit and scope of the invention.

I do not herein claim the tack feeding and 35 driving mechanism, *per se*, illustrated, described and claimed in my co-pending application Serial No. 276,398, filed August 30, 1905, nor do I herein claim the lasting mechanism, *per se*, herein described, but which is described, illustrated and claimed in my co-pending application Serial No. 564,455 filed June 1, 1910.

Having thus explained the nature of the invention, and described a way of constructing 45 and using the same, although without attempting to set forth all of the forms in which it may be made, or all of the modes of its use, I declare that what I claim is:—

1. A machine of the character described, 50 comprising fastener-inserting mechanism, bodily movable mechanism for gripping the upper, and means in consequence of which the bodily movement of said gripping mechanism automatically causes the operation of 55 the fastener-inserting mechanism.

2. A machine of the character described, 60 comprising a gripper for engaging the upper of a shoe, power-driven fastener-inserting mechanism controlled by said gripper, and manually actuated means in consequence of which the said gripper is caused to engage said upper.

3. A machine of the character described, 65 comprising a normally inactive power-driven fastener-inserting mechanism, tripping

mechanism for rendering said fastener-inserting mechanism active, and a bodily movable gripper adapted to be bodily moved by the shoe and to operate said tripping mechanism, to effect the actuation of the 70 fastener-inserting mechanism.

4. A pulling-over machine comprising a frame, a gripper on said frame located so that there is a free space beneath it for the manipulation of the shoe whereby the shoe 75 may be moved when its upper is engaged by the gripper to position the upper upon the last, and fastener-inserting mechanism controlled by the gripper whereby a fastener may be inserted through the upper into the 80 insole to secure the pulled-over portion of the upper to the insole.

5. A pulling-over machine comprising a frame, fastener-inserting mechanism on said frame, and a gripper positioned in front of 85 said fastener-inserting mechanism and having a clear space therebeneath for the manipulation of a shoe, said gripper comprising a movable jaw having a shoulder or abutment against which the innersole may 90 be placed and is adapted to serve as a fulcrum about which the shoe may be rocked at any time while the upper is held between the jaws of the gripper.

6. A pulling-over machine comprising a 95 frame, fastener-inserting mechanism on said frame, a gripper positioned adjacent to said fastener-inserting mechanism and having a clear space therebeneath for the manipulation of a shoe, and a movable shoulder or 100 abutment adjacent to said gripper against which the innersole may be placed and which is adapted to serve as a fulcrum about which the shoe may be rocked, and which may be bodily moved by the shoe, at the 105 will of the operator, to effect the actuation of the fastener-inserting mechanism.

7. A machine of the character described, comprising a tack-driver, a longitudinally movable nipple through which the driver is 110 adapted to reciprocate, a gripper jaw pivoted to the nipple and adapted to move therewith, means for actuating said jaw to cause it to close upon material inserted between it and the nipple, a tack-race having 115 its end adjacent to said nipple, a tack-feeder connected to the nipple and actuated by said nipple when the latter is moved, a continuously moving power-transmitting device adapted to actuate said driver, and means 120 connected to said nipple and adapted by the actuation thereof to cause said power-transmitting device to actuate said driver, said means being adapted when actuated thereby to cause said power-transmitting 125 device to actuate said driver a predetermined number of times.

8. A machine of the character described, comprising a frame having an overhanging head with a clear space adjacent it for the 130

manipulation of a shoe, a gripper on said head for gripping the upper and comprising depending pivoted jaws against whose lower ends the face of the insole of a shoe 5 may be placed, said jaws when opened having a substantially vertical space between them for the insertion of the edge of the upper of the said shoe, one of said jaws having a front portion at an angle to its 10 end to constitute a corner or abutment about which as a fulcrum the shoe may be rocked bodily to position and draw the upper around the last, means for operating said jaws, and fastener-inserting mechanism adjacent 15 said jaws and adapted to be operated to insert a fastener through the upper into the insole.

9. A machine of the character described, comprising a rotatable shaft, a projection 20 on said shaft, a stop-finger normally spring-held in the path of rotation of said projection, a lever of which one arm is connected to said stop-finger to withdraw it from the path of rotation of said projection, an oscillatory bell-crank lever pivoted to and carried by the other end of said lever, a member adapted to be moved by a shoe 25 to engage one arm of said bell-crank lever, and a fixed stop in the path of the other 30 arm of said bell-crank lever.

10. A power-fastener-driving machine of the character described, comprising a fastener-driving mechanism, including a nipple with a passage therethrough for the fastener, a driver, and mechanism for actuating said driver, a gripper comprising co-acting jaws which, when in closed position, have their faces substantially parallel to the line of movement of the fastener, one 35 of said jaws being formed on the nipple and the other being movable relatively thereto, means for operating the movable jaw of the gripper, an abutment rigid with one of the jaws about which as a fulcrum 40 the shoe may be rocked to draw the upper, one of the said instrumentalities being mov-

able, and means controlled by said movable element to effect the automatic operation of the driver.

11. A power-fastener-driving machine of 50 the character described comprising a fastener-driving mechanism, including a nipple with a passage therethrough for the fastener, a driver, and mechanism for actuating said driver, a gripper comprising co-acting jaws which, when in closed position, have their faces substantially parallel to the line of movement of the fastener, one of 55 said jaws being formed on the nipple and the other being movable relatively thereto, treadle-actuated mechanism for operating the movable jaw of the gripper, and a stationary frame supporting said movable parts in their operative positions, one of 60 the jaws of the gripper having a corner which constitutes an abutment, about which the shoe, grasped by the operator, may be rocked to draw the upper around the last and positioned with respect to the nipple to 65 receive a fastener.

12. A machine of the character described, comprising a gripper having coacting jaws of which one is movable with a clear space therebeneath for the free manipulation of a shoe, means for inserting a fastener into the shoe, the opposing faces of the said jaws when closed being substantially parallel to the path of the fastener whereby when the jaws are closed upon the edge of the upper the shoe may be moved manually so as to 70 bring the stretched portion of the upper which lies upon the insole, into the path of the fastener, means for operating the gripper, and means controlled by the gripper for 75 causing the automatic operation of the fastener-driving mechanism.

In testimony whereof I have affixed my signature, in presence of two witnesses.
